Primary Examiner — Patricia A Palasik(74) *Attorney, Agent, or Firm* — Banner & Witcoff, Ltd.(57) **CLAIM**

The ornamental design for an industrial robot, as shown and described.

DESCRIPTION

FIG. 1 is a front-right-top perspective view of an industrial robot showing our new design;
 FIG. 2 is a rear-left-bottom perspective view thereof;
 FIG. 3 is a rear-right-top perspective view thereof;
 FIG. 4 is a front-left-bottom perspective view thereof;
 FIG. 5 is a front-left-top perspective view thereof;
 FIG. 6 is a rear-left-top perspective view thereof;
 FIG. 7 is a right side view thereof;
 FIG. 8 is a left side view thereof;
 FIG. 9 is a top plan view thereof;
 FIG. 10 is a bottom view thereof;
 FIG. 11 is a rear view thereof; and,
 FIG. 12 is a front view thereof.
